CLAIM

The ornamental design for a garden planter, as shown and described.

DESCRIPTION

FIG. 1 is a front elevational view of a garden planter showing our new design, the rear being identical; FIG. 2 is a side elevational view thereof, both sides being identical;

FIG. 3 is a top plan view thereof;

FIG. 4 is a bottom plan view thereof; and

FIG. 5 is a reduced perspective view thereof, the flowers being shown in broken lines for illustrative purposes only.

FIG.3

FIG.2

FIG.4
